UNITED STATES PATENT OFFICE.

PERCY GAVIN, OF NATIONAL SANITARIUM, TENNESSEE.

RADIO AMPLIFYING RECEIVER.

Application filed October 17, 1925. Serial No. 63,023.

To all whom it may concern:

Be it known that I, PERCY GAVIN, a citizen of the United States, residing at National Sanitarium, in the county of Washington and State of Tennessee, have invented certain new and useful Improvements in Radio Amplifying Receivers, of which the following is a specification.

The present invention relates to receivers primarily intended for use in radio communication; and the primary object of the invention is to provide a device of this character for producing, reproducing, or magnifying speech or any other tone with sufficient amplitude and volume, and at the same time reducing to a minimum all undesirable sounds and disturbances, by reason of the softness of which the tones are produced.

A further object of the invention is the provision of an improved receiver of the character specified, wherein the aforementioned results are obtained by the magnetic coupling of a pair of co-acting diaphragms serving as independent pole pieces of independent permanent magnets of the receiver, in the magnetic field of the electro-magnets of the receiver.

Other objects and advantages of the invention will be apparent during the course of the following detailed description, taken in connection with the accompanying drawing, forming a part of this specification, and in which drawing:

Figure 1 is an inside plan view of the improved receiver, the cap and diaphragms being removed for showing the arrangement of various elements of the device.

Figure 2 is a cross sectional view taken on line 2—2 of Figure 1.

Figure 3 is a fragmentary sectional view on line 3—3 of Figure 1.

Figure 4 is a fragmentary sectional view on line 4—4 of Figure 1; and,

Figure 5 is a diagrammatic view illustrating the manner in which the diaphragms are connected so as to serve as independent pole pieces of the independent permanent magnets.

Referring to the drawing in detail, where-in for the purpose of illustration is shown but one embodiment of the principle involved, and wherein similar reference characters designate corresponding parts throughout the several views; the letter A designates generally a receiver of the "watchcase"

type, embodying a casing B, diaphragmatic means C and actuating means D therefor supported within the casing B.

Referring particularly now to the casing B, the same consists of inner and outer nested cups 10 and 11 respectively, which are preferably but not essentially formed of magnetic metal, and which cups are insulatively separated one within the other as by a thin cup 12 formed of any suitable insulating material. These cups 10 and 11 are of the usual configuration as that of the present "watchcase" type of receivers, having cylindrical side walls and flat bottom portions. As will be observed upon viewing Figures 2, 3 or 4, the cup members 11, 12 and 10 decrease in height in the respective order given, thus disposing the upper edge of the spacing insulating cup 12 below the upper edge of the outer cup 11 and above the upper edge of the inner cup 10. The object in so disposing the cups with their upper edges in stepped relation will be subsequently set forth. A cap or cover 13 formed of hard rubber or a suitable composition, and provided with a central aperture for egress of the sound waves, has carried inwardly of the flange 14 thereof an internally threaded metal ring 15 of substantially L-shaped in cross section, for threaded connection with external screw threads provided adjacent the upper edge of the outer cup 11. This metal ring 15 has formed on its inwardly extending leg portion, a depending annular pressure ring 16 preferably of a like diameter and thickness as that of the inner cup 10. Thus it will be seen that when the cover 13 is turned upon the cup 11, the under face of the pressure ring 16 will be disposed in direct confronting relation with the upper edge of the inner cup 10. The outer cup 11 may be provided with diametrically arranged apertures 17 for detachable reception of one end of a head band as now in common use with certain types of head sets. A thin disc of insulating material 18 is fitted in the cup 10 for insulatively spacing the actuating means D from contact with any metal portion of the casing B.

Referring now to the diaphragmatic means C, the same embodies a pair of disc shaped diaphragms 20 and 21 insulatively held in adjustable spaced relation to one another as by a compressible insulating ring 110

22 of a diameter to snugly fit within the outer cup section 11. These diaphragms 20 and 21, and which may be respectively termed inner and outer diaphragms, may be 5 formed of soft iron or steel of the desired thickness, and as will be observed in Figure 2, the inner diaphragm 20 is of slightly less diameter than the diameter of the diaphragm 21. It will here be noted that the insulat- 10 ing cup 12 extends past the upper edge face of the inner metal cup 10 for a distance equal to the thickness of the inner diaphragm 20, and that the inner diaphragm 20 is of a diameter to snugly fit within the insulating 15 cup 12 and rests at its outer edge in conducting relation upon the upper edge face of the metal cup 10; while the outer dia- phragm 21 is of a diameter to snugly fit within the outer metal cup 11. Thus it will 20 be seen that the diaphragm 20 is held in conducting relation with the inner cup 10, while the diaphragm 21 which is insulatively spaced from the diaphragm 20 and inner cup 10, is conductively connected with the 25 outer cup 11 as by the metal ring 15. It will readily be apparent that upon rotation of the cover 13 in one direction or the other will act upon the yieldable ring 22 in a manner for varying the spacing between the dia- 30 phragms 20 and 21.

With reference now to the actuating means D, the same embodies independent, preferably laminated steel permanent magnets 23 and 24 of semi-circular shape in 35 formation, and which are arranged concentric within the inner cup 10 of the casing B, and with their like poles slightly spaced from one another as clearly illustrated in Figure 1. For the purpose of further explanation, the poles of the permanent magnets 23 and 24 have been indicated as plus (+) and minus (--) upon the drawing. Extending through the lamine at the minus pole of the permanent magnet 24, is a flat 40 or countersunk head bolt 25 which extends through the insulating disc 18 and has its head seated in a tapering aperture 26 in the bottom wall of the inner cup 10. This bolt 25, which is provided with the lock nuts 27, 45 serves as means for retaining the minus pole end of magnet 24 in position, and also serves as a connecting conductor between the minus pole of the magnet and the inner metal cup 10. This construction is clearly 50 illustrated in Figure 3. Extending through the lamine at the plus pole of the permanent magnet 23, is a flat or countersunk head bolt 28 which extends through an insulated aperture 29 in the inner cup 10, and has its 55 head seated in a tapering aperture 30 in the bottom wall of the outer cup 11 for serving as means for retaining the plus pole end of the magnet in position and also serving as a 60 connecting conductor between the plus pole 65 of the magnet and the outer metal cup 11.

This bolt 28 is provided with lock nuts 31, and which arrangement of the bolt is clearly illustrated in Figure 4.

Secured one to the minus pole of the mag- 70 net 23, and one to the plus pole of the mag- net 24, and as by flat head bolts 32, are similarly formed soft iron L-shaped brackets each embodying base sections 33 provided respectively with pole pieces 34 and 34'; said pole piece 34 thus being made minus 75 and serving as a minus terminal of the permanent magnet 23, and the pole piece 34' thus being made plus and serving as a plus terminal of the permanent magnet 24. These unlike pole pieces 34 and 34' extend with 80 their ends into close proximity to the inner diaphragm 20 and have positioned there- about the usual coil windings 35 and 36 re- spectively for varying the magnetic field of 85 their respective pole pieces in the usual manner. Extending through the base sections 33 of the L-shaped brackets and insulated there- from, and through and insulated from the base of the casing B, are terminal binding 90 posts 37 and 38 which are electrically con- nected at their inner ends to the windings 35 and 36 respectively. These binding posts 37 and 38 also serve as means for securing the minus and plus pole ends of the permanent 95 magnets 23 and 24 respectively in position in the base of the casing B, and also act as means for retaining the cup sections 10, 11 and 12 in nested relation.

In cases where the receiver is to be em- 100 ployed as a unit for a "loud speaker", the cover 13 may form the base of the horn, and if the horn be formed of metal, the conductor ring 15 may be eliminated and the metal base of the horn made to serve for completing the circuit between the outer 105 cup 11 and the outer diaphragm 21.

Referring particularly to Figure 5 of the drawing, it will be seen that the outer diaphragm 21 becomes in reality, the plus pole of the magnet 23; whereas the inner 110 diaphragm 20 becomes in reality, the minus pole of the magnet 24, thus making the dia- phragms 20 and 21 of unlike poles. Thus 115 it will be seen that each of the diaphragms 20 and 21 becomes independent pole pieces of the magnets 23 and 24, magnetically coupled in the field of the poles 34 and 34'; and 120 possessing the diaphragms with a greater amplitude of resonant vibration when ef- fected by the field of the poles 34 and 34'; attraction when unlike charged, and repel- 125 ling when like charged. This action accounts for the clearness of which the sound is pro- duced, and why undesirable peaks and static effects which occur in a fraction of a second, are reduced to a minimum and neutralized be- 130 fore they have time to mature into intense sound waves.

Various changes may be made to the 135 specific form of invention herein shown and

described, without departing from the spirit of the invention or the scope of the claims.

I claim:

1. In an amplifying receiver for telephony, diaphragmatic means, and magnetic means for influencing said diaphragmatic means, and including electromagnets magnetically connected to the diaphragms of the latter, so that said diaphragms act as poles of the magnetic means.

2. In an amplifying receiver for telephony, diaphragmatic means, and magnetic means for influencing said diaphragmatic means, and including electromagnets having pole pieces of unlike polarity magnetically connected to the diaphragms of the latter, so that said diaphragms act as poles of the magnetic means.

3. In an amplifying receiver for telephony, diaphragmatic means, and magnetic means for influencing said diaphragmatic means, and including electromagnets so magnetically connected to the diaphragms of the latter, so that said diaphragms act as unlike poles of the magnetic means.

4. In an amplifying receiver for telephony, diaphragmatic means, and magnetic means for influencing said diaphragmatic means, and including electromagnets having pole pieces of unlike polarity so magnetically connected to the diaphragms of the diaphragmatic means, that said diaphragms act as unlike poles of the magnetic means.

5. In an amplifying receiver for telephony, diaphragmatic means including insulatively spaced apart parallel diaphragms, and magnetic means for influencing said diaphragmatic means, and including electromagnets having unlike pole pieces so magnetically connected to the diaphragms, that said diaphragms are made the opposite poles from the respective pole pieces to which they are magnetically connected.

6. An amplifying receiver for telephony comprising a casing, independent permanent magnets arranged in said casing, electromagnets arranged in said casing and each having its pole piece magnetically connected to one pole of said permanent magnets, and diaphragmatic means, including diaphragms magnetically connected to the opposite poles of the permanent magnets and arranged in the magnetic field of the poles of the electromagnets.

7. An amplifying receiver for telephony comprising a casing, independent permanent magnets arranged in said casing, electromagnets arranged in said casing and each having its pole piece magnetically connected to unlike poles of the permanent magnets, and independent diaphragms magnetically connected one to each of the opposite poles of the permanent magnets and disposed in

the magnetic field of the poles of the electromagnets.

65

8. An amplifying receiver for telephony comprising a casing embodying nested metallic cups insulated one from the other, permanent magnets arranged within the inner cup and each having one pole thereof connected respectively to the inner and outer cups of the casing by metallic connecting elements, electromagnets in the casing and having their pole pieces connected to the opposite poles of the permanent magnets, and diaphragmatic means including spaced diaphragms arranged in the magnetic field of the pole pieces of the electromagnets, and with said diaphragms connected respectively to the inner and outer metallic cups of said casing.

75

9. An amplifying receiver for telephony comprising a casing embodying nested cups formed of magnetic metal and insulated one from the other, a pair of permanent magnets of semi-circular formation arranged in the inner cup with their like poles in close related relation, electromagnets having their pole pieces connected to unlike poles of the permanent magnets, means for magnetically connecting the opposite unlike poles of the permanent magnets one to the inner cup and one to the outer cup, and spaced diaphragms contacting one with each of said cups and disposed in the magnetic field of the pole pieces of said electromagnets.

85

10. An amplifying receiver for telephony comprising a casing embodying nested cups formed of magnetic metal and a spacing cup insulatively supporting one cup within the other, a diaphragm in contact at its edge with the edge of the inner cup, a second diaphragm in contact at its edge with the edge of the outer cup and spaced from the first diaphragm, means for retaining the diaphragms in adjusted position, and magnetic means within said casing for actuation of said diaphragms, and magnetically connected to the diaphragm through said cups.

95

11. An amplifying receiver for telephony comprising a casing embodying nested cups of unlike depths, a diaphragm in contact at its edge portion with the edge of one of said cups, a second diaphragm in contact at its edge with the edge of the other cup, a compressible ring disposed between the diaphragms at their edge portions, a cover provided with an egress opening, threaded upon the outer cup and bearing upon the edge portion of the outer diaphragm for varying the spacing between the diaphragms upon rotation of the cover, and magnetic means within the casing for actuation of said diaphragms.
